ADJUSTABLE FOLDED GARMENT SUPPORT FOR LUGGAGE CASES

George A. Viehmann, New Providence, and Charles C. Harrison, Glen Ridge, N. J., assignors to Newark Rivet Works, Newark, N. J.

Application January 30, 1956, Serial No. 562,098

3 Claims. (Cl. 190—41)

This invention relates to improved means for supporting folded garments within a luggage case.

This invention has for an object to provide an improved folded garment support for use in a luggage case or the like in association with garment hanger means, whereby to equip a compartment of such case or the like for the non-shifting and non-wrinkling carriage of one or more men's suits or women's garments.

The invention has for a further object to provide a novel frame structure for disposition within the fold of garments suspended by hanger means in a compartment of a luggage case or the like, whereby the folded garments will be supportedly suspended by a frame member, when the case or the like is hand carried, against shifting and wrinkling displacement from smoothly folded condition; means being provided for pivotally mounting the frame member within said compartment of the case or the like, so as to permit out swinging thereof from the latter, including means for adjusting the operative position of the frame member within said compartment, and means to lock the frame member in selectively adjusted position within said compartment, whereby to accommodate the supporting position of the frame member relative to folded garments of different sizes, or to a plurality of folded garments.

The above and other objects will become apparent from a reading of the following description of this invention in connection with the accompanying drawings which show an illustrative embodiment thereof, in which drawings:

Fig. 1 is a fragmentary plan view of a luggage case in open condition, a compartment of which is equipped with the novel adjustable folded garment supporting frame structure of this invention, which frame structure cooperates with garment hanger means mounted in said compartment.

Fig. 2 is a longitudinal vertical sectional view, taken on line 2—2 in Fig. 1, and showing the folded garment supporting frame as adjusted to support a single relatively long coat of a man's or woman's suit; Fig. 3 is a fragmentary view, similar to that of Fig. 2, but showing the folded garment supporting frame as adjusted to support a single relatively short coat of a man's or woman's suit; and Fig. 4 is a similar view showing the garment supporting frame as adjusted to support a plurality of folded suit coats.

Fig. 5 is a fragmentary vertical cross-sectional view, taken on line 5—5 in Fig. 2, but drawn on an enlarged scale.

Referring to the drawings, in which like characters of reference indicate corresponding parts, the reference character 10 indicates one section of a luggage case and 11 the other section thereof which is connected with section 10 by suitable hinge means 12, whereby said sections can be closed together, and releasably secured in closed condition by suitable fastener catches 13, all as familiar to the art. One of said sections, e. g. section 10, is provided with a carrier handle 14 mounted on its external side or front wall 15.

As shown, the section 10 of the luggage case provides a compartment within which may be packed the folded garments desired to be carried therein. Fixed centrally upon the inner face of the internal side or back wall 16 of the section 10 is a bracket member 17, in connection with which one or more garment hangers 18 can be detachably coupled for extension therefrom into said compartment.

The garment fold supporting frame structure comprises a pair of stationary hanger pieces 20 which are respectively affixed to the compartment end walls of section 10 of the case in offset relation thereto, and so as to be adjacently spaced in relation to the internal side or back wall 16 of said compartment, whereby to extend downwardly into the interior of said compartment perpendicular to the plane thereof. Generally, as shown, the open tops of the sections of the case are bounded by marginal metallic framing 21, having inwardly projecting portions 22 parallel to the planes of said sections. In such type of case construction, the hanger pieces 20 are provided, at their upper ends, with angular anchor lugs 23 to seat on said projecting portions 22, so that said hanger pieces depend therefrom, and so that the bodies thereof are offset from the adjacent end walls of the compartment in which they are located. Said anchor lugs 23 are affixed to said projecting portions 22 of a case section framing by fastening bolts 24 or other equivalent fastening means. In other types of case construction, e. g. frameless types, the hanger pieces 20 can be affixed by their upper end portions to the compartment end walls in any suitable manner, whereby the dependent bodies thereof are offset relative to said end walls. The dependent bodies of the hanger pieces 20 are provided with longitudinal slots 25, which are disposed thereby perpendicular to the plane of the compartment in which they are located.

The frame member of the garment fold supporting frame structure, which is generally indicated by the reference character 26, comprises a pair of side bars 27, the inner end portions 28 of which are provided with longitudinal slots 29 of substantial length. The main bodies of said side bars 27 are connected with said slotted inner end portions 28 by inwardly offsetting bends 28'. Affixed to and for extension between the outer extremities of the side bars 27 is an outer cross-bar 30. Preferably, although not essentially, additional like cross-bars 31 are affixed to and between said side bars 27 in suitably spaced apart relation, thus providing a frame member of panel like form.

The respective slotted inner end portions 28 of the side bars 27 of the frame member 26 are disposed across the slotted bodies of the respective hanger pieces 20, and are pivotally and adjustably connected with the latter by combined pivoting and locking means. Each pivoting and locking means comprises a pivot and lock bolt 32 arranged to extend through intersecting portions of the slots 25 and 29 of a hanger piece 20 and the inner end portion 28 of an engaging side bar 27 (see Fig. 5). The bolt 32 is provided with a head 33 to abut the back of the hanger piece 20, and engaged on the free end of said bolt 32, which projects from the engaging side bar end portion 28, is a thumb nut 34. Preferably a washer 35, through which the bolt 32 extends, is interposed between the hanger piece 20 and said side bar end portion 28, and another like washer 36 is interposed between the latter and the thumb nut 34.

In the use and operation of the above described folded garment supporting means of this invention, the luggage case or the like being opened to give access to the section 10 thereof that provides the compartment in which garments are to be packed, the thumb nuts 34 being loosened, the frame member 26 is out swung from said

compartment to the position thereof shown by broken lines in Fig. 2.

Assuming it is desired e. g. to pack a man's suit, the hanger 18 is detached from the bracket member 17, and the coat (together with the vest if included) is draped upon the hanger in well known manner, and the trousers may also be folded over the cross-bar of said hanger 18, or otherwise packed into the compartment. The coat being draped on the hanger 18, the hanger therewith is then returned to attached relation to the bracket member 17, whereupon the skirts of the coat are smoothly extended and the coat sleeves smoothly folded into place (see broken line representation of the coat in Fig. 1). The coat being thus disposed, the frame member 26 is now down swung into the case compartment so as to overlie the coat, whereupon the skirts of the latter are in-folded around the terminal cross-bar 30 and over the frame member. If the coat is of a long size, the frame member 26 is shifted outwardly toward the external side or front wall 15 of the compartment, by sliding the slotted inner end portions 28 of the side bars thereof over the bolts 32, thus increasing the effective length of the frame member for accommodation of such long coat (see Fig. 2). If the coat is of comparatively shorter size, the frame member 26 is shifted inwardly toward the internal or back wall 16 of the compartment, thus decreasing its effective length in accommodation to such shorter coat (see Fig. 3). If a single suit is packed, the frame member 26 is lowered, consonant to the bulk thereof, by sliding the bolts 32 downwardly in the slotted hanger pieces 20 (see Figs. 2 and 3). If, however, more than one suit is packed, the frame member 26 is raised by sliding the bolts 32 upwardly in the slotted hanger pieces 20, to accommodate the level of said frame member to the additional bulk of the folded garments (see Fig. 4).

From the above, it will now be understood that the folded garment supporting means of this invention is easily, quickly and universally adjustable, both as to its effective length and the operative level thereof, as may be required to accommodate its supporting relation to the packed garments. Once a desired adjustment of the frame member 26 is attained, the same can be locked, against pivotal movement and against displacement from its adjusted position, by tightening home the thumb nuts 34, so as to clamp the side bars 27 to the hanger pieces 20.

The luggage case or the like may be provided with a hinged partition member 49 that can be swung down over the packed section 10, and suitably secured in closed condition thereover, thus separating the garment packed compartment of the case or the like from the other case section 11 and its contents.

After the case or the like is packed and closed, when the same is carried by the handle member 14 in suspension therefrom, the garment fold engaging cross-bar 30 of the frame member 26 will be uppermost, and will function to suspendingly support the folded garments against shifting and wrinkling displacement from their smoothly arranged condition.

Having now described our invention, we claim:

1. In a luggage case or the like having a section thereof to provide a folded garment containing compartment equipped with garment hanger means dependent from the back wall of said compartment, means adapted to be disposed within the fold of garments carried by the hanger means, whereby to suspend the folded garments by the

fold thereof when the case or the like is carried, said means comprising a frame member having side bars provided with longitudinally slotted inner end portions, longitudinally slotted hanger pieces affixed to opposite end walls of the case compartment in offset relation thereto and in adjacently spaced relation to the back wall of said case compartment and perpendicular to the plane of said case compartment, and combined pivoting and locking means cooperative with corresponding intersecting slotted hanger pieces and slotted inner end portions of the frame member side bars, whereby to connect said frame member in both pivotal and adjustable relation to said hanger pieces for extension therefrom toward the front wall of the case compartment when disposed in garment fold engaging position, said latter means being manipulatable to lock said frame member in selected adjusted operative position.

2. The combination according to claim 1, wherein the combined pivoting and locking means comprises bolts to respectively engage through intersecting slotted hanger pieces and slotted inner end portions of the frame member side bars, and thumb nuts on said bolts manipulatable to releasably clamp the frame member side bars to the hanger pieces against movement of the former relative to the latter.

3. In a luggage case or the like having a section thereof to provide a folded garment containing compartment equipped with garment hanger means dependent from the back wall of said compartment, means adapted to be disposed within the fold of garments carried by said hanger means, whereby to suspend the folded garments by the fold thereof, said means comprising hanger pieces affixed to opposite end walls of the case compartment in offset relation thereto, whereby to depend intermediate the open top and bottom wall of the case compartment perpendicular to the plane of the latter and adjacently parallel to the compartment back wall, the dependent body portions of said hanger pieces being provided with vertically disposed slots, a frame member including side bars, inner end portions of respective side bars being adapted to engage across said respective hanger pieces and having horizontal slots to intersect the slots of the latter, headed bolts extending through the intersecting slots of interengaged hanger pieces and inner end portions of the frame side members, and thumb nuts on said bolts, all whereby said frame member is pivotally supported by said hanger pieces and adjustably shiftable relative thereto both horizontally and vertically, whereby to both predetermine the effective length of the frame member and the level of operative disposition of said frame member within and parallel to the plane of the case compartment, said thumb nuts being manipulatable to releasably clamp the frame member to the hanger pieces, whereby to secure the former against displacement from a selected adjusted operative position thereof within the case compartment.
